C. DOBBS.
CAR COUPLING.
APPLICATION FILED NOV. 25, 1908.

927,334.

Patented July 6, 1909.

UNITED STATES PATENT OFFICE.

CHARLES DOBBS, OF DALLAS, TEXAS.

CAR-COUPING.

No. 927,834.

Specification of Letters Patent.

Patented July 6, 1909.

Application filed November 25, 1908. Serial No. 464,475.

To all whom it may concern:

Be it known that I, CHARLES DOBBS, a citizen of the United States, residing at Dallas, in the county of Dallas and State of Texas, have invented new and useful Improvements in Car-Couplings, of which the following is a specification.

This invention relates to car couplings, the object of the invention being to provide a simple and effective device of this character by which two cars can be separably connected together in a secure manner.

In the drawings accompanying and forming part of this specification I show in detail one advantageous form of embodiment of the invention which, to enable those skilled in the art to practice the same, will be set forth at length in the following description, while the novelty of the invention will be included 20 in the claims succeeding said description.

Referring to said drawings: Figure 1 is a perspective view of a car coupling involving my invention and showing the same connected with a car. Fig. 2 is a side elevation of 25 said coupling. Fig. 3 is a top plan view of the coupling, the pin-carrier being shown in horizontal section. Fig. 4 is a longitudinal view partly in section. Fig. 5 is a detail sectional view hereinafter more particularly 30 described. Fig. 6 is a perspective view of a locking slide or detent. Fig. 7 is a side elevation of the pin-carrier. Fig. 8 is a perspective view of the link.

Like characters refer to like parts throughout the several figures.

In Fig. 1 of the drawings I have shown the end portion of a car as 2 with which my coupling may be connected in any desirable manner, said coupling including in its construction a chambered draw-head as 3 the chamber of which is denoted by 4. The forward portion of the lower wall of the chamber 4 has a downwardly and forwardly inclined link-lifting face as 5.

The pin of the coupling is designated by 6 and it is connected in some desirable way to a pin-carrier as 7. The pin-carrier is represented as consisting of an open or substantially skeleton-like frame the side bars 45 of which are adapted to straddle the draw-head, the latter having notches as 8 to receive the vertically-disposed side bars of said pin-carrier 7, by virtue of which tripping or swinging movement of said pin-carrier is 50 prevented. In the present case, the upper end or head portion of the pin 6 is swiveled

to the upper cross-bar of said pin-carrier. To the pin-carrier or to the upper portion of the pin a chain as 9 may be connected, said chain being illustrated as also connected to 60 a crank-arm as 10 fastened to the rock-shaft 11 supported by suitable bearings on the end of the car 2, said shaft also having attached thereto a hand-lever as 12 by which the shaft can be operated to raise the pin-carrier 7 and 65 thereby also move the pin 6 out of co-operative relation with a link as 13.

The chain 9 may be provided with an upward continuation as 14 adapted to extend to the roof of the car, whereby the pin-carrier can be elevated for uncoupling purposes from said roof, this being of particular advantage when the car equipped with the coupling is in motion. The pin 6 has a movement 70 through a perforation or hole as 15 in the upper side of the draw-head 3 and it may be provided with a buffer as 16 adapted to strike the upper side of said draw-head when the pin passes through one of the openings in the link 13, as indicated in Fig. 4. This 75 buffer 16 may be of rubber or any other suitable material.

If desired, the pin-carrier 7 may be equipped with a handle as 17 constituting in the present case a continuation of the lower 80 cross-bar thereof and by grasping which said pin-carrier can be elevated. The link 13 will, as will be clear, have two perforations or 85 holes through it, through which pins as 6 of opposite couplers are adapted to pass, and 90 the pin 6 is shown in Fig. 4 as extended through one of the perforations of the link 13.

In Figs. 1 and 2 the pin-carrier 7 and pin 6 are represented as being up and they are maintained in this position in a positive 95 manner by a detent such as that denoted in a general way by 18 and shown in detail in Fig. 6.

The detent or locking device 18 is shown as supported for sliding movement by a bracket 100 as 19 supported by the draw-head 3 at one side and at or near the top thereof, the bracket 19 being of substantially right-angular form in cross section, as shown best in Fig. 5. The sliding detent or locking device 18 has a forward extension as 20 of less width than the body of said detent and it terminates in an inwardly extending projection 21 which has a play in a groove or channel as 22 formed near the outer or forward end of the 105 draw-head 3. The detent 18 is provided with a rearward extension 23 of somewhat

reduced diameter and which is represented as extending through an eye as 24 extending from the side face in the foreground of the draw-head 3 in Fig. 2. The eye 24 and channel 22 guide the sliding detent 18 in a horizontal path. The rear or inner end of the body of the detent 18 and the shoulder or inner face of the projection 21 are adapted to limit the inward or rearward movement of 10 the detent 18, the projection 21 and the body of the detent for this purpose engaging the pin-carrier 7 and eye 24, respectively. On the upper side of the detent 18 I have shown an inwardly extending flange as 25 equipped 15 with an upwardly projecting pin as 26 constituting a handle by which the said detent 18 can be readily manipulated. The forward end of this flange 25 is beveled as at 27 and this beveled end 27 constitutes the operative or effective portion of the detent 18, being co-operative with a notch as 28 in one of the side bars of the skeleton-like pin-carrier 7.

In Figs. 1 and 2 the pin 6 and its carrier 7 are shown as up, the detent 18 being at this time in its forward position and the beveled portion 27 being seated in the notch 28 so that the detent will hold the pin and pin-carrier up; at this time the extension 20 of the 25 detent will be forward of the front or outer face of the draw-head 3 where it can be engaged by the draw-head of a companion coupling mounted on a car moving toward the first-mentioned draw-head. When the 30 moving draw-head has nearly approached the stationary draw-head, the moving draw-head will strike the forward end of the extension 20 and, on the continuation of such movement, will move the detent 18 inwardly 35 or rearwardly and will carry the beveled portion 27 out of the notch 28 and will thereby release automatically the pin-carrier 7 so that the pin 6 can then pass through the perforation, hole, or opening in the link 13 which, in 40 the meantime, has been positioned within the stationary draw-head.

In Fig. 4 the pin 6 is shown as projected through one of the openings of the link 13, the latter hanging at a downward angle from 45 the pin. It will be assumed that this link is moving toward a stationary draw-head. When the free portion of the link 13 strikes the inclined face 5 of the companion draw-head, said inclined surface will, on the motion of the moving draw-head, cause the link to assume a horizontal position and, at about

the time this takes place, the pin on the stationary draw-head is released to effect the coupling. The flange 25 overlies and slides upon the upper surface of the draw-head 3. 60 When the two cars are coupled there is ample provision for vertical and side motion thereof.

What I claim is:

1. A car coupling comprising a chambered draw-head, a coupling-pin, a carrier for said coupling pin, operatively associated with said draw-head, and a slidable detent at one side of the upper portion of the draw-head and provided with an inwardly projecting portion, the pin-carrier having a notch to receive the inwardly projecting portion of said detent, and the latter, when in its operative position, having an extension projecting beyond the forward or outer end of said draw-head. 75

2. In a car coupling, a draw-head, a coupling pin, a movable carrier for the coupling pin, an angular bracket carried by the draw-head, and a slidable detent supported by said bracket and having a flange overlying the top of the draw-head, the pin-carrier having a notch and the flange having a beveled portion to enter said notch to hold the pin-carrier and pin in elevated positions. 80

3. In a car coupling, a draw-head provided with an angular bracket, a coupling pin, a pin-carrier movably associated with said draw-head, a detent slidably supported by said bracket and adapted to engage the pin-carrier to hold the latter and the pin in elevated positions, said detent having a forward extension adapted, when the detent is in its operative position, to extend beyond the forward or outer end of the draw-head, a handle on the detent, and a handle on the pin-carrier. 95

4. In a car coupling, a draw-head, a coupling pin, a pin-carrier movably associated with said draw-head, and a sliding detent provided with a frame overlying the top of the draw-head, the pin-carrier having a notch, and the forward portion of said flange being adapted to enter said notch to hold the pin-carrier and pin in their elevated positions. 100

In testimony whereof I have hereunto set my hand in presence of two subscribing witnesses.

CHARLES DOBBS.
